UNITED STATES PATENT OFFICE.

EDWARD J. CHIRGWIN, OF PORTLAND, OREGON.

ILLUMINATED SIGN.

936,234.

Specification of Letters Patent.

Patented Oct. 5, 1909.

Application filed February 18, 1907, Serial No. 258,157. Renewed March 15, 1909. Serial No. 423,536.

To all whom it may concern:

Be it known that I, EDWARD J. CHIRGWIN, a citizen of the United States, and a resident of Portland, in the county of Multnomah and State of Oregon, have invented a new and useful Improvement in Illuminated Signs, of which the following is a specification, reference being had to the accompanying drawings as constituting a part thereof.

10 The object of my invention is to produce an illuminable sign which will be of ornamental appearance viewed in day light, and which will also be effective and attractive at night time. The day light attractiveness or effect is obtained by the usual color schemes, also by exterior formation of letters; but the night effect is obtained by giving to the sign the appearance of being composed of black sign-characters set out by a 20 halo-like luminous margin.

To this end my sign consists of a sign box or case within which is contained the illumination means—electric lamps, gas flames, etc., the face of the sign case being a solid 25 wall of opaque material, and the light being emitted through such wall by slits or perforations arranged to conform to the contour lines of the members of the letters or characters; the latter screening the direct 30 rays of the light and causing the same to be diverged and diffused so as to be emitted over the outline-margins of the members of the sign-characters in the form of a halo, and thereby causing the sign-character itself 35 to stand out, as it were, from such halo like a silhouette. In other words the light rays issuing from the interior of the sign case are screened by the sign character and restrained so as to impinge only upon the 40 medial contour lines of the backs of the respective members of the sign characters, and the faces of such backs and of the face of the sign-case are adapted to reflect and diffuse the light rays so as to bring about the effect 45 described. To attain this effect the parts of my sign are constructed and arranged as below set forth.

In the drawings, Figure 1 is a perspective of my sign as a whole, the two ends being 50 represented as broken apart, so that the left end portion may represent my sign as it appears in day light and the right end portion as it appears in the night time; parts of the sign-characters, or letters, are further removed and indicated in broken outline, so as to disclose the arrangement of

the perforations in the face of the sign case under the sign character; Fig. 2 is a longitudinal section looking into the interior of the sign case through one of the perforated faces thereof and against the backs of the sign characters; Fig. 3 is a transverse section of my sign; and Figs. 4 and 5 are details of modifications of construction.

Referring now to the reference letters: my 65 sign consists of a rectangular box or case *a*, in which are placed, at suitable intervals, a series of electric lamps *b*. These lamps may be placed opposite to each other, as shown in Fig. 2, or so that the lamps on one side of 70 the wall of the sign-case will come intermediate of the lamps supported by the opposite wall; and the number of lamps will depend upon the size of the letter and the intensity of the light desired. The letters or 75 sign-characters *c* are affixed to the outer face *i* of the sign-case by short arms *d*, so as to project some distance in front as illustrated, for example, in Fig. 3. Following the form or contour of the members of the letter or 80 sign character, the face *i* is provided with perforations, which may consist of slits *e*, or a series of contiguous perforations *f*. The perforations in either case being so arranged as to be located along the medial lines 85 of the respective members of the sign-characters, and so that the rays of light emitted there through will impinge only upon the medial lines of the back of such members; the sign characters being of such width that the 90 margins of the members thereof will project some distance beyond such perforations, and thus screen the direct light rays and diverge the same so as to impinge upon the face of the sign case, to be from there projected over the outline-margins of the sign-character in the form of a halo, substantially as depicted in the portion of the sign 95 at the right, shown in Fig. 1. In order to obtain brilliant effects it is preferable to 100 coat the back of the letters or sign-characters with a reflecting surface, because if too dark too much light would be absorbed, and the face *i* of the sign-case should be treated in like manner, for the same purpose. 105

In order to establish some rule by which the relative size of the perforation in the face of the sign-case and the position of the sign-characters covering such perforations may be governed, I have ascertained that in 110 using, for example, letters of say, six inches in height, the same should be placed about $\frac{1}{4}$

- of an inch in front of the face of the sign-case and the letters should be made of such width as to cause the margins thereof to project about $\frac{1}{2}$ inch beyond the margin of 5 the slits or perforations; and for each fraction of an inch the sign-character is set farther out from the face of the sign-case, the margins of the slits or perforations should be moved the same distance inward.
- 10 In short, the parts of the sign must be so arranged as not to disclose the slits or perforations when viewing the sign from the front, at the usual angles of vision. Furthermore the letters must not be set out too far 15 from the face of the sign-case, and the slits or perforations must be of sufficient size to emit ample light.

In referring to a reflecting surface to be given to the backs of the sign-characters and 20 the face of the case, I meant that the same could be painted white, or otherwise colored with a suitable reflecting pigment.

The sign-characters can be made of wood, metal or glass. When made of the latter, the 25 sign-characters would have to be made sufficiently opaque to properly screen the direct light rays and bring about the desired effect.

The exposed faces of the sign-characters and their back ground of case-wall may be 30 painted to render the same as ornamental as desired in the day time. The backs of the sign-characters may be made flat as represented in the sectional figure 5, or such backs may be made with angular faces as represented in Fig. 4, for the purpose of causing 35 a greater divergence of the light-rays emitted through the slits of the wall a' . The exterior beveled faces h of the sign-characters seen in Figs. 4 and 5 and representing the 40 letter I, are optional, that is to say, their object is merely to give an ornamental appearance to the face of the sign-characters when seen in the day light, but not otherwise entering into the scheme of my invention.

45 It is to be noted that the described illumination means in no wise affect the appearance of the sign-characters in day light.

I claim:

1. In an illuminable sign consisting of a 50 case, illumination means within the case and

a sign character or characters affixed some distance in front of the case-wall, the case-wall being perforated along the medial contour lines of the members of the sign-character and the latter covering said perforations so as to cause the light rays impinging on the under side of the sign-characters to be diverted over the margins of its members in the form of a luminous halo.

2. In an illuminable sign, a wall perforated along the medial contour lines of the members of the sign characters, means for emitting light rays through the perforations, and a sign-character or characters set out over such perforations and arranged to 65 cover the latter, whereby the light rays impinging on the under side of the sign-character are diverted over the margins of its members in the form of a luminous halo.

3. In an illuminable sign, a wall perforated along the medial contour lines of the members of the sign-characters means for emitting light rays through the perforations, and a sign character or characters set out over such perforations and arranged to 75 cover the latter, the under side of the sign-character and the face of the wall being adapted to reflect the light rays, whereby the light rays impinging on the under side of the sign-characters are diverted over the 80 margins of its members in the form of a luminous halo.

4. In an illuminable sign, a wall, perforated along the medial contour lines of the members of the sign-character, means for 85 emitting light rays through the perforations and a sign-character or characters set out over such perforations and arranged to cover the same, the under side of the sign-characters being made with reflecting angles, 90 and the face of the wall being made with a reflecting surface, whereby the light rays impinging on the under side of the sign-character are diverted over the margins of its members in the form of a luminous halo. 95

EDWARD J. CHIRGWIN.
